PREFABRICATED BAY WINDOW UNIT

Iino Kaneko, Iwao Shima, and Takanori Kato, Tokyo,
Japan, assignors to Misawa Homes Institute of Research
& Development, Tokyo, Japan

Filed Sept. 30, 1974, Ser. No. 510,796

Claims priority, application Japan Apr. 2, 1974

Term of patent 3½ years

Int. Cl. D25—92

U.S. CL. D25—52

FIG. 1

FIG. 2

6—

FIG. 3

FIG. 4

FIG. 5

FIG. 6

FIG. 7

FIG. 1 is a top plan view of a prefabricated bay window unit showing our new design;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a cross sectional view on line 6—6 of FIG. 2; and

FIG. 7 is a perspective view thereof.

The left side elevational view is a mirror image of FIG. 3, and is omitted.

The dotted line showing of a wall is for illustrative purposes only.

We claim:

The ornamental design for a prefabricated bay window unit, as shown and described.
